BATTERY CARRYING STRAP

Sam Goldman, Brooklyn, N. Y.

Application December 7, 1938, Serial No. 244,338

2 Claims. (Cl. 294—104)

This invention relates to lifting and carrying devices and more especially to a device for lifting and carrying a storage battery of the type used in automobiles.

5 A feature of the invention is an improved clamp for the terminal of a storage battery of the type described which is easily positioned on and which provides a firm and secure grip on the terminal and absolutely prevents the clamp from slipping off. Another feature of the invention is such a clamp formed so that it will not bend or mutilate the top of the terminal and will take a secure grip at a position on the terminal near the battery. Another feature of the invention is a two-part clamp in which the parts are mounted to rock easily with reference to each other but which are permanently secured to each other. Another feature is a clamp having two parts which are simple to manufacture and provide a powerful grip on the terminal of the battery. Other objects will appear as the description proceeds.

Reference is made to the drawing for an illustration of one embodiment of the invention, in which,

25 Figure 1 is a perspective view showing the improved device attached to the terminal posts of an electrical storage battery.

Figure 2 is a perspective view showing the clamp attached to one of the terminals.

30 Figure 3 is a side view showing the clamp attached to one of the terminals.

Figure 4 is a side view showing the clamp in the released position partially removed from a terminal.

35 Figure 5 is a top view showing the clamp attached to a terminal.

The electric storage battery A is of the type used in automobiles and has two diagonally disposed terminals B, each of which is in the form 40 of a truncated cone. A strap handle 10 is preferably made of fabric set in rubber and supports at each end by a permanent fastening, such as rivets or the like, a metal loop 11 to the lower end of which my improved clamp is pivotally 45 secured by means of a transverse slot 12 formed near one end of a flat-metal element 13 of the clamp. Each element 13 has a short flat upward extension 14 narrower than the slotted end of the element, bent away from the perpendicular 50 towards the end slot to form an acute angle with the element 13 and also has two side stops 15 at the bottom of the upward extension 14. At the top, the extension 14 is bent in the opposite direction to form the flat terminal-engaging extension 16 which forms an obtuse angle with the

extension 14 and which has centrally of the right end a cut-away portion 17 which forms a part of a circle and is engageable with the side wall of a terminal B in the clamping position. The extension 16 is stamped on the top at both sides 5 near the extension 14 to form sidewardly extending lugs 18 after the extension 16 has been inserted from the bottom through a slot 19 formed transversely near the left end of the other clamping element 20, which is a flat piece having, near the opposite end, a circular opening 22 which fits down over a terminal B and preferably approximately to the bottom thereof.

The two elements 13 and 20 of the clamp are 15 permanently fixed together but so that they can rock pivotally in the slot 19 with reference to each other, the rocking or pivotal motion being limited by the stops 15 and the lugs 18. The aperture 22 easily admits the top of the terminal B because of the frustro-conical form of the 20 terminal.

Referring to Figures 1, 2, 3 and 5, the clamping action when the hand grasps the strap 10 to lift the battery A is clearly illustrated. The curved edge 17 engages the wall of the terminal B. The 25 extension 14 engages the left side of the slot 19. The top surface of clamping element 13 engages the left edge of clamping element 20 which forms a fulcrum so that the weight of the battery A and the opposed upward lift on the strap 10 tend 30 to press the outside edge of opening 22 into the terminal B and simultaneously rock the edge 17 of the extension 16 tightly down against and into the opposite wall of the terminal B. When the battery A is set down and the end of the strap 35 10 is dropped down, as shown in Figure 4, the edge 17 of extension 16 is tilted up and away from the terminal B, and thereupon the clamping element 20 may be easily slipped up off the terminal B.

Having disclosed my invention and realizing that in view of my disclosure many modifications, substitutions, and omissions of parts may readily occur to those skilled in the art, I do not limit myself except as in the appended claims.

40
45
I claim:

1. A battery-carrying strap having clamps for engaging the terminals of an electric storage battery, each clamp comprising in combination, a flat piece having an opening at one end engageable in a transverse plane with a frustro-conical terminal of the battery and a transverse slot near the other end, and an element passing thru said slot and rockable in said slot, having one end above said piece and engageable with 50 55

and exerting downward pressure on said terminal and the other end extending below said piece and attached to said strap, an intermediate portion between said ends and passing through said transverse slot disposed at an obtuse angle with reference to said terminal end and disposed at an acute angle with reference to the top of said strap end, said intermediate portion and said opening end of said element being narrower than the remainder of the element, and a lug on the side of said opening end of said element and overlying an end of the transverse slot.

2. A battery-carrying strap having clamps for engaging the terminals of an electric storage battery, each clamp comprising in combination, a flat piece having an opening at one end engageable in a transverse plane with a frustro-

conical terminal of the battery and a transverse slot near the other, an element passing thru said slot and rockable in said slot, having one end above said piece and engageable with and exerting downward pressure on said terminal, the other end extending below said piece and attached to said strap, and an intermediate portion between said ends and passing through said transverse slot and disposed at an obtuse angle with reference to said terminal end and disposed at an acute angle with reference to the top of said strap end, said intermediate portion and said strap end of said element being wider than the remainder, and a pair of lugs oppositely disposed on the side of said terminal end of said element and overlying the ends of said transverse slot.

SAM GOLDMAN.
